UNITED STATES PATENT OFFICE.

RUDOLPH A. BOEHM, OF ERIE, PENNSYLVANIA, ASSIGNOR OF ONE-THIRD TO FREDERICK W. WYATT AND ONE-THIRD TO GUSTAVE RAPP, BOTH OF ERIE, PENNSYLVANIA.

THREADING-DIE HOLDER.

1,119,676.

Specification of Letters Patent.

Patented Dec. 1, 1914.

Application filed April 11, 1914. Serial No. 831,190.

To all whom it may concern:

Be it known that I, RUDOLPH A. BOEHM, a citizen of the United States, residing at Erie, in the county of Erie and State of Pennsylvania, have invented certain new and useful Improvements in Threading-Die Holders; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to threading die holders, and particularly to that type of said die holders which are adapted to automatically open, after a desired number of threads have been cut.

20 The objects of my invention are to construct an automatically opening die holder with a floating shank, and with improved adjusting mechanism, so that various diameters of screws can be made by the same die. These and other features of my invention will appear hereafter in the specification and claims, and are illustrated in the accompanying drawings, in which:—

25 Figure 1, is a plan view of the face of my die-holder, with a portion of the cam-ring broken away. Fig. 2, is a central section of the same, on the line $\alpha-\alpha$ in Fig. 1. Fig. 3, is a plan view of the same, with the cam-ring removed. Fig. 4, is a view partially in side elevation and partially in central section, on the line $y-y$ in Fig. 3. Fig. 5, is a plan view of the same with the cam-ring, dies and adjusting ring removed. Fig. 6, is a side view of the same, showing an attachment for cutting threads on a tapering screw. Fig. 7, is a section of the same on the line $z-z$, looking in the direction of the arrow in Fig. 4.

30 In these drawings, A, indicates the body of the die-holder, which is provided with a cylindrical chamber A', in the rear end thereof, and a central opening A², from the face thereof through into said chamber. The face thereof is provided with slots A³, in which are secured adjustable bearing plates α , which are secured in adjusted position by means of screws α' (see Fig. 3). The face end of the body A, is reduced in diameter so as to have a shoulder α^2 , into which are cut grooves α^3 , in which are placed

35 springs α^4 , as shown in Figs. 2 and 5. Upon the shoulder α^2 , I place a ring B, which is provided with studs B', (shown in broken lines in Fig. 3, and in section in Fig. 5) projecting into the grooves α^3 , and are engaged by the studs B' on the ring B. The ring B, is also provided with a slot B², in which is placed a slideable block B³, having a transverse slot b, (see Fig. 3). I also provide adjusting screws B⁴, by means of which the block B³, may be retained in adjusted position in the slot B², in the ring B.

40 Within the slots A³, in the body A, I place thread cutting dies C, which are secured to chaser plates C', by means of screws c; said chaser plates projecting under the adjustable face plates α , in said slots A³, so as to be retained in said slots by said face plates α . The outer ends of said chaser plates α , are provided with up-turned extensions C²; I also provide springs C³, (see Fig. 3) which engage said extensions C², and operate to assist in moving the dies C, backward away from the work when desired.

45 Upon the ring B, I place a cam-ring D, which is provided with cam-surfaces D', which engage the outer ends of the dies C, and operate to force them inwardly toward their work. The body A, within the cam-ring D, is preferably of less diameter than the interior diameter of the cam-ring, so that the cam-ring D, will be in spaced concentric relation to said body, so that should the work being threaded be slightly off of center, the cam-ring D, and dies C, will center themselves upon it. The under face of the cam-ring D, is cut away sufficiently to receive the extensions C², on the extensions C', and is provided with cam-grooves D², which receive the up-turned projections C², on the die-chasers C', and operate in conjunction with the springs C³, to force the dies C, backward. The cam-ring D, is provided with a stud pin D³, which projects into the slot b, in adjustable block B³, so that the cam-ring D, may be rotatively adjusted with relation to the ring B. The ring B, is also provided on its under surface with a recess B⁵, (see Fig. 3) for the purpose hereinafter set forth.

50 Within the cylindrical chamber A', I place a floating member E, having a central opening E', therethrough. In the central opening A², in the body A, I secure a sleeve

2

E^2 , which extends into the central opening E' , in the floating member E. The floating member E, is non-rotatably placed within the body A, by means of key-balls F, in 5 grooves F' , in the member E, and F^2 in the body A. To retain the balls F, within the grooves F' — F^2 , I provide keepers F^3 , as shown in Figs. 2 and 7. In the floating member E, I provide holes G G, in which I 10 place spring-pressed pins, G' , which are maintained in contact with the body A, by means of springs g . I also provide recesses H H, partly in each of said members E, and the body A, and I provide on the member 15 E, small plates e e' , which extend into said recesses H H, and I secure on the rear end of the floating member E, a hollow shank or stem J, by means of which the die holder may be supported in the machine tool in 20 which it is desired to operate the die holder. In the recesses H H, I place springs h h' . I then secure on the rear end of the body A, a collar or ring K, by means of small screws k , (see Fig. 2) which prevents the springs h 25 and h' , from falling out of the recesses H H, and compresses said springs between said ring K, and the plates e e' , and thereby suspending the floating member E, between the springs g g' , and the springs h h' . The 30 recess H, which receives the end of the plate e' , is bored upward entirely through the shoulder a^2 , and in this recess, a rod L, is placed, which passes through the spring h' , and the plate e' , and terminates in a head 35 L', provided on its upper end with two bearing shoulders; the shoulder l , being on the center of said shaft L, and the shoulder l' , being set away from the center of said shaft, so that the shoulder l' , does not allow 40 the springs a^4 , to rotate the ring B, quite so far as the shoulder l , and one or the other of said shoulders l and l' , can be used as desired by turning the lever L^2 . This is what 45 is known to the trade as a "rough and finish" attachment, where the lever L^2 , and the shoulder l' , are in the position shown in the drawings, the dies are supposed to rough-cut the threads, and when the lever 50 L^2 , is operated to present the shoulder l , to act as a stop to the ring B, they are supposed to finish-cut the threads. When it is 55 desired to cut a thread, the cam-ring D, is rotated backward against the springs a^4 — a^4 , by means of a handle d , until the shoulders l l' , on the head of the spring pressed shaft L, snaps into the recess B^5 , in the ring B, which forces the dies inward to their cutting position; their cutting position relative 60 to the diameter of the screw to be cut, being fixed by operating the adjusting screws B^4 — B^4 . When it is desired to open the dies, a backward pull on the work being threaded compresses the springs h and h' , and withdraws the shoulders l l' , out of the 65 recess B^5 , in the ring B, and permits the 70

springs a^4 — a^4 , to operate the two rings B and D, in the direction indicated by the arrows n , in Figs. 1, 3, 4 and 6, which forces the dies backward from the work.

In Fig. 6, I show an attachment for cutting a thread on a tapered screw. On the cam-ring heretofore described, I place a plate M, which by means of the bolt M' , can be adjusted to give the edge of said plate any degree of inclination to the axis of the die-holder described. Secured on the body A, there is a guide N, in which there is secured a spring-pressed slide N' , adapted to be normally maintained in an extended position by a spring N^2 , a pin n' , passing through a slot in said slide behind the springs. Upon this slide there is a hinged arm N^3 , which is provided with a spring to maintain it normally in contact with a stop shoulder n^2 , on the slide N' . The arm N^4 , is 80 provided with longitudinally adjustable mechanism N^5 , by means of which the length of said arm N^2 , may be varied, the said arm being engaged by the inclined edge of the plate M, thereby limiting the rotation of the cam-ring D, by the springs a^4 , as hereinbefore described. In the operation of this taper attachment the adjusting mechanism N^5 , is operated to adjust the cam-ring D, to control the cutting dies in making a 85 cut as desired, and when the dies start the thread on the work, the slide N' , is engaged by the work holder or some part of the machine tool moving axially in unison with the work, (not shown) and is thereby moved 90 backward, thereby carrying the arm N^2 , backward along the inclined edge of the plate M, which permits the cam-ring D, to be gradually rotated by the springs a^4 , in the direction of the arrow n , thereby gradually opening the dies C, during the cutting of the threads, until the arm N^2 , passes off of the end of the plate M, and permits the cam-ring D, to quickly open and withdraw 95 the dies C, from their work. When the 100 taper attachment is used, the shaft L, is removed so that the plate M, and arm N^4 , are the stops which control the action of the springs a^4 — a^4 .

Secured on the face of the body A, there 115 is a plate ring O, which secures the cam-ring D, in place on the die-holder.

Having thus described my invention so as to enable others to construct and operate the same, what I claim as new and desire 120 to secure by Letters-Patent of the United States, is:—

1. In a device of the class described, a body having radial slots in the face thereof and a cylindrical chamber in the opposite 125 end, dies in said radial slots, a cam-ring, cams thereon adapted to engage said dies and move them inward and outward, a shank in said cylinder chamber, a collar secured on the rear end of said body to retain 130

- 5 said shank within said cylindrical chamber, spring mechanism adapted to maintain said shank in spaced relation to the inner end of said cylindrical chamber, and spring mechanism adapted to normally maintain 70 said shank in spaced relation to said collar, and means to prevent said shank from rotating within said chamber, substantially as set forth.
- 10 2. In a device of the class described, a body having a cylindrical chamber therein, thread-cutting radial dies slidably mounted in the face thereof, a cam-ring mounted on said body, cams thereon adapted to give inward and outward movement to said threading dies, spring mechanism adapted to operate said ring to open said dies, lock mechanism mounted in said body adapted to control said ring to maintain said dies in their 15 innermost position, a shank, a head thereon slidably and non-rotatably mounted in the cylindrical chamber in said body, a collar on said body adapted to retain said shank head within said chamber, spring mechanism adapted to maintain said shank in 20 spaced relation to the inner end of said cylindrical chamber, and spring mechanism adapted to normally maintain said shank in spaced relation to said collar, and means on 25 said head to engage said lock-mechanism and operate the same when said head is moved toward said collar to release said cam-ring and open said threading dies, substantially as set forth.
- 30 3. In a device of the class described, a body having a cylindrical chamber therein, radially slidable threading dies mounted in the face of said body, means to retain said dies therein, up-turned extensions on said dies, a cam-ring mounted on said body, cams thereon engaging said dies and extensions thereon for imparting radial movement thereto, spring mechanism adapted to operate said cam-ring to open said dies, a shank head 35 slidably and non-rotatably mounted in said body, a collar secured on said body adapted to retain said head in said chamber, spring mechanism adapted to maintain said shank head in spaced relation to the inner end of 40 said cylindrical chamber, and spring mechanism adapted to normally maintain said shank-head in spaced relation to said collar, a spring-pressed rotatable locking bolt slidably mounted in said body and said collar, 45 a plurality of shoulders on the upper end of said bolt, adapted to stop the backward movement of said cam-ring at different points of rotation thereof, means to rotate said bolt, means on said shank-head to operate said bolt to release said cam-ring and means to retain said cam-ring on said body, substantially as set forth.
- 50 4. In a device of the class described, a body member, a ring having a recess in its under side, mounted thereon, spring mecha- 55 nism to actuate said ring in one direction, a slotted slidable block mounted in the recess in said ring, screw mechanism to control said block, a spring-pressed slidable lock-bolt mounted in said body adapted to enter 60 the recess in the under side of said ring when the same has been operated in one direction, means to release said bolt from engagement with said ring, radially slidable thread-cutting dies secured in the face of said body 65 member, spring mechanism engaging said dies and adapted to move said dies outwardly, a cam-ring rotatably mounted on said body member, cams thereon adapted to give radial movement to said dies, a stud 70 on said cam-ring adapted to enter the slot in the slidable block in spring actuated ring, and means to retain said cam-ring in place on said body, substantially as set forth.
- 75 5. In a device of the character described, a body member having a cylindrical chamber therein and a central opening therethrough, radially slidable thread-cutting dies mounted in the face thereof, a cam-ring mounted on said member, means to operate 80 said ring, cams thereon adapted to give radial movement to said dies, a sleeve secured in said central opening and extending into said cylindrical chamber, a shank-head slidably and non-rotatably mounted in said 85 chamber having a central opening therethrough to receive said sleeve, a collar secured on said body adapted to retain said head within said chamber, spring mechanism adapted to suspend said head mid-way 90 between the inner end of said chamber and said collar, a spring-pressed locking bolt slidably mounted in said body member adapted to engage and lock said cam-ring when said ring is operated in one direction, 95 and means on said shank-head to engage and operate said bolt to release said cam-ring, substantially as set forth.
- 100 6. In a device of the class described, a body member, radially slidable thread-cutting dies secured in the face thereof, a rotatable cam-ring mounted on said member, cams thereon adapted to give radial movement to said dies, spring mechanism adapted to rotate said ring in one direction, an adjustable plate secured on said ring, a guide secured on said body member, a spring-pressed slide mounted in said guide, and means on said slide adapted to engage 105 said adjustable plate to control the spring actuated rotation of said cam-ring, substantially as described.
- 110 7. The combination in a device of the class described, of a body member, radially movable threading dies secured in the face thereof, a cam-ring mounted on said body, cams thereon adapted to give radial movement to said dies, a plate secured on said cam-ring having a surface inclined to the axis of said body, a bar slidably mounted on said body 115 120 125 130
- 60 65 70 75 80 85 90 95 100 105 110 115 120 125 130

- parallel to the axis of said body adapted to be engaged by some moving part of the machine, upon which the device is used, a spring to operate said bar in one direction, 5 and adjustable mechanism carried by said bar adapted to engage the inclined surface on said plate to control the rotation of said cam-ring in one direction, substantially as set forth.
- 10 8. In a device of the class described, a body member having radial slots in the face thereof, bearing-plates removably secured in said slots, die-plates in said slots extending under said plates, upturned extensions on 15 said plates, thread-cutting dies between said bearing-plates and secured to said die-plates, a cam-ring mounted on said body, cams thereon adapted to engage said dies and said upturned extensions, and means to operate 20 said cam-ring, substantially as set forth.
9. In a device of the class described, a body member having a cylindrical chamber therein, radially movable thread cutting dies mounted in the face thereof, means to operate 25 said dies, a shank head slidably mounted in said member, a collar on said body to retain said head in said chamber, co-incident longitudinal grooves in the wall of said body member and periphery of said shank
- head, balls in said grooves, and spring mechanism adapted to suspend said head midway between the inner end of said chamber and said collar, substantially as set forth. 30
10. In a device of the character described, a body member having a cylindrical chamber therein, radially movable threading dies in the face thereof, means to operate said dies, a shank head in said chamber, spring pressed pins in said shank head adapted to engage the inner end of said chamber, ball- 35 race-ways between the wall of said chamber and said head, balls in said race-ways, and springs between said head and said collar operating in opposition to said spring pressed pins, substantially as set forth. 40
11. In a device of the class described, a body member, radially movable threading dies secured in the face thereof, a cam-ring secured thereto adapted to move said dies radially, 45 and means to rotate said cam-ring, substantially as set forth.

In testimony whereof I affix my signature, in presence of two witnesses.

RUDOLPH A. BOEHM.
